United States Patent Office

Des. 214,895

Patented Aug. 12, 1969

214,895

EXTENSION TO A BOW SIGHT

Fred Hamilton, 9467 Bullion Way,
Orangevale, Calif. 95662

Filed Oct. 16, 1967, Ser. No. 9,002

Term of patent 14 years

Int. Cl. D22—02

U.S. Cl. D22—5

FIG. 1

FIG. 4

FIG. 2

FIG. 3

FIG. 5

FIGURE 1 is a side elevational view of an extension to a bow sight, showing my new design, the opposite side being substantially similar in appearance;

FIGURE 2 is a front perspective view;

FIGURE 3 is a top plan view, the bottom plan being substantially similar in appearance;

FIGURE 4 is a rear elevational view; and,

FIGURE 5 is a front end elevational view.

I claim:

The ornamental design for an extension to a bow sight, as shown and described.
